Emmanuel Scheyer
ATTORNEY

UNITED STATES PATENT OFFICE

ALBERT EDGAR BLACKMAN, OF MOUNT VERNON, NEW YORK

MAIL BOX

Application filed September 8, 1927. Serial No. 218,193.

This invention relates to mail-boxes for one or two-family houses. It is of a type to be set in the vestibule wall of a house. Boxes of this kind are usually provided with a slot 5 in the front face of the box in which the mail is deposited. They are shallow and it is easy for unauthorized persons to withdraw the mail through the slot without opening the box.

10 In my construction there is an upper door which can be opened without a key and a lower door which requires a key to open it. The upper door is provided with an inwardly extending hood, the top of the hood having a slot extending diagonally across it. Mail is deposited by the postman through the slot, and falls down into the box opposite the lower and locked door where it is inaccessible unless one has the key. When the upper door 20 is pulled open, magazines and other packages too large for the slot can be laid upon the top of the hood.

Certain features of the construction shown herein but not claimed form the subject matter of my copending applications Serial Nos. 168,632 and 196,254.

Other objects and advantages will become apparent upon a further study of the description and drawing in which:—

30 Fig. 1 is a front elevation of my box, Fig. 2 is an end elevation, the dot and dash lines showing the door in open position, Fig. 3 is a plan looking up at the bottom of the box, Fig. 4 is a front elevation of the hood removed 35 from the upper door, Fig. 5 is a side elevation of the hood, and Fig. 6 is a plan view of the top of the hood showing the diagonal slot.

In the particular embodiment of my invention illustrated herein, a mail-box is shown with two compartments, said box being suitable for a two-family house. The same general construction can be followed in a one compartment box suitable for a one-family house.

The box comprises side walls 7 and 8, bottom 9, back 9a and top 10. A front frame 11 is fastened to flanges 12 formed on the front of said top, bottom and sidewalls.

50 For the two-family mail-box, a partition

wall 13 is provided for dividing the box into two full depth compartments. An upper or master door 14 extends substantially for the width of the two compartments and closes the front of said compartments. Individual or 55 tenant doors 15 close the front of the lower compartments. The upper door 14 is formed with a hinge loop 16 at its lower end which comes about a hinge rod (not seen), the ends of which are pivotally supported in the upper portion of socket pieces 17. Socket pieces 17 are fastened to front frame 11. The lower doors 15 are formed each with a hinge loop 18 at its upper end which comes about a hinge rod (not seen), the ends of which are 60 pivotally supported in the lower portion of socket pieces 17. Individual or tenant locks 19 are provided for lower doors 15.

Upper door 14 is provided with two hoods denoted generally by the numeral 20, one hood adapted to come into each compartment when said door is closed. Each hood 20 comprises a front portion 21 which is welded or otherwise fastened to the back of upper door 14. Extending from front portion 21 are triangular wings 22 forming the side portions of the hood. The top portion 23 is provided with a diagonally extending slot 24 for the insertion of the mail. A knob 25 is provided on the upper door for convenience in opening and closing said door.

When the postman wishes to deposit mail in the box, he swings down upper door 14 by means of knob 25, exposing slot 24, through which he inserts the mail. Door 14 is shown by dot and dashed lines in open position in Fig. 2. If he has a magazine, such as denoted by the numeral 26, which is too large to pass through slot 24, he lays it upon the top 23 of hood 20. It is to be noted that top 23 is below the upper edge of door 14. This enables the upper portion of door 14 to keep magazine 26 from falling off top 23. Each tenant has a key to fit his lock 19 on the lower door 15, by means of which he can open his door 15 and remove whatever mail has been deposited in his compartment.

The upper rear edge of hood 20 acts as a stop for limiting the opening of door 14.

I claim:—

1. In a mail-box having a plurality of compartments open at the front, a master door, for closing the upper portions of all 5 of said compartments, a plurality of hoods extending inwardly of the box and fixed upon the master door, a hood corresponding to each compartment and adapted to come within its corresponding compartment when 10 the door is closed, each hood having a top and side portions in fixed relation to each other and being provided with a slot in its top for the introduction of mail, said hoods, except for their slots, obstructing access to 15 the interior of their corresponding compartments when the master door is open.

2. In a mail-box having a partition wall for dividing the box into compartments open on one face, a door movably mounted 20 upon the box for closing the open face, spaced hoods mounted upon the inside of said door, each hood having a top and side portions in fixed relation, a hood corresponding to each compartment and adapted to come within its 25 corresponding compartment when the door is closed, said partition coming in between the space between the hoods, each hood being provided with a slot in its top for the introduction of mail, said hoods, except for their 30 slots, obstructing access to the interior of their corresponding compartments when said door is open.

Signed at New York city, in the county of Bronx and State of New York, this 6th 35 day of Sept., A. D. 1927.

ALBERT EDGAR BLACKMAN.
